CONTAINER CLOSURE

George Yates, Jr., Glendale, Calif., assignor to Bennett-
Industries, Inc., Peotone, Ill., a corporation of Delaware

Filed May 29, 1967, Ser. No. 7,299

Term of patent 14 years

(Cl. D9—264)

FIGURE 1 is a top plan view of a container closure showing my new design;

FIGURE 2 is a side elevational view;

FIGURE 3 is a sectional view taken on the line 3—3 of FIGURE 1, and

FIGURE 4 is a sectional view taken on the line 4—4 of FIGURE 1.

The essential features of the design are shown in full lines.

I claim:

The ornamental design for a container closure, as shown and described.
